UNITED STATES PATENT OFFICE.

THOMAS AMACKER WOMACK, OF MANCHAC, LOUISIANA.

DESIGN FOR A PLOW-POINT.

SPECIFICATION forming part of Design No. 32,707, dated May 22, 1900.

Application filed April 23, 1900. Serial No. 14,062. Term of patent 14 years.

To all whom it may concern:

Be it known that I, THOMAS AMACKER WOMACK, a citizen of the United States, residing at Manchac, in the parish of East Baton Rouge and State of Louisiana, have invented and produced a new and original Design for Plow-Points; and I do hereby declare the following to be a full, clear, and exact description of the invention, such as will enable others skilled in the art to which it appertains to make and use the same.

My invention relates to a new and original design for a plow-point; and it consists in the novel design hereinafter described and shown.

The design consists, essentially, of a plow-point having two curved divergent portions meeting at their front ends in the central line of the point and having at their rear ends angular shoulders and curved extensions or wings somewhat wider than said divergent portions, there being at the forward or meeting ends of said divergent portions a tapering forward projection, as seen in the accompanying drawings.

In the accompanying drawings, which illustrate my design, Figure 1 is a front perspective view of a plow-point embodying my design, and Fig. 2 is a perspective view as seen from one side of the front.

A A designate the two divergent portions meeting at their forward ends and having the tapering forward projection *a* at the angle of their meeting. A' A' designate the shoulders at the rear ends of the said divergent portions A A, and A² A² designate the curved wings extending from the rear ends of the said divergent portions A A.

What I claim as my invention is—

The design for a plow-point substantially as herein described and shown in the accompanying drawings.

In testimony whereof I affix my signature in presence of two witnesses.

THOMAS AMACKER WOMACK.
